his attorney.

UNITED STATES PATENT OFFICE.

WILLIAM A. BROWN, OF NEW YORK, N. Y., ASSIGNOR TO HIMSELF, THOMAS G. BROWN, AND THOMAS B. BROWN, OF SAME PLACE.

DESIGN FOR A CUP.

SPECIFICATION forming part of Design No. 22,580, dated July 4, 1893.

Application filed November 11, 1892. Serial No. 451,718. Term of patent 3½ years.

To all whom it may concern:

Be it known that I, WILLIAM A. BROWN, a citizen of the United States, and a resident of the city of New York, in the county and State of New York, have invented and produced a new and original Design for a Cup, of which the following is a specification, reference being had to the accompanying drawing, forming a part thereof.

10 The drawing represents the design applied to a metal cup.

The leading feature of my design consists in a raised (or repoussé) border, which encircles the article, and this border is composed 15 of an endless series of overlapping conventional hearts.

Referring to the figure which shows a sil-

ver cup, A, is the ornamental border encircling the cup, and composed of a wreath or series of conventional hearts, C, C, presenting 20 a repoussé effect, and each of the said hearts overlaps its neighbor heart on the one side, and is overlapped by its neighbor on the other side, as is apparent in the drawing. The ornamental effect is heightened by connecting 25 the points of the hearts by overlapping and underlapping scrolls, D, D.

What I claim is—

The design for cups substantially as herein shown and described.

WILLIAM A. BROWN.

In presence of—

CHARLES L. LINCOLN,
ARTHUR L. KENT.
